PHIL SHERIDAN, OF CHICAGO, ILLINOIS

CARBURETOR

Application filed July 11, 1923. Serial No. 650,744.

One object of the invention is to provide a carburetor construction for the internal combustion motor of an automobile or the like having a relatively high velocity flow in the mixing tube when the motor with which the carburetor is associated is idling or when the automobile is being driven at a very low speed, for the adequate and effective mechanical subdivision of the entrained fuel and its thorough intermixing with the air with which it is associated.

Also, it is essential to keep the suction at high speeds of the automobile at a comparatively low point, or, stated somewhat otherwise, it is desirable to avoid an excessive rarefaction or suction at high speeds of the car.

If we have the desired high velocity flow when the motor is idling, caused by the suction, unless some special provision is made, an excessive or undue suction would be present at a high speed of the engine, with a resultant reduction of engine compression and a consequent lessening of maximum power.

It would be preferable, if it were possible of accomplishment, to maintain a substantially constant or practically unvarying velocity in the mixing chamber of the carburetor at all engine speeds, and in my device this is substantially effected.

To attain the above specified object, the new and improved carburetor has a mixing tube of comparatively small cross section to assure the required high velocity flow therethrough, and a supplemental, air-inlet, constant-weight valve is employed, which does not start or begin to open until the suction has reached a predetermined amount, for example, that corresponding to approximately a fourteen-inch water column. This explains how the high initial velocity is secured.

When the suction tends to increase, such valve opens and, by the admission of air, keeps the suction down, which otherwise would become excessive, such valve being employed for the purpose of maintaining an air velocity in the mixing chamber which varies as little as possible.

Obviously the fuel ought to be introduced in proportion to the amount of air passing

through the carburetor, and to do this, or to govern this action, the extent of travel of the valve is employed as an adjusting means to effect the correct ratio of fuel to air.

Although the suction in the mixing tube is more or less constant, the suction at the mouth of the fuel orifice is not uniform, but varies substantially as the square of the air velocity through the carburetor.

Under normal idling conditions, the suction in the starting-well, that is, the chamber or compartment with which the fuel discharge openings connect and into which the fuel is delivered, is less than that corresponding to one-half inch water column, and hence only the lower fuel opening is operative, and proper idling can be readily and easily secured by adjustment of the needle-valve controlling the low-speed lower fuel nozzle.

The use of the lower fuel nozzle alone will give a progressively leaner mixture as the engine speeds up, and to compensate for this unsatisfactory condition a second fuel passage or discharge is needed which will supply a progressively richer mixture.

To accomplish this result, the first fuel nozzle is located below the fuel level of the carburetor supply and the second nozzle is positioned above such level.

To modify the fuel ratio curve when the two nozzles are operative, I employ a tapered metering cone mounted on the constant-weight valve referred to, such cone being arbitrarily or appropriately shaped to enrich the mixture or modify the fuel curve at the particular points desired.

The second jet being rendered temporarily useless or put out of commission, the first or lower jet is adjusted by manipulation of its needle-valve or equivalent means to obtain a smooth and satisfactory slow engine speed, and then the valve controlling the second or higher opening is adjusted for high speed.

The first jet mixture being too lean for high speed, the second jet mixture gradually compensates or progressively enriches the mixture, which becomes leaner step by step were the first jet used alone.

A further object of the invention is to provide a carburetor which will permit the motor

to start easily under all conditions of service, and to the accomplishment of this result the starting-well is filled by gravity just as soon as the engine is stopped, and hence a rich mixture is automatically delivered to the engine each time it is started.

Another aim of the invention is to so construct the carburetor that quick acceleration of the automobile may be had, which means that the gaseous mixture should be temporarily enriched to secure such desired acceleration.

Other objects of the invention are the securing of a maximum economy by a carburetor which is simple in structure, which is easily regulated, which does not get out of adjustment, and which may be made at relatively small cost.

The carburetor is economical in action because there are perfect means for almost exact compensation, thus maintaining a proper ratio of fuel to air under all conditions.

This in the new carburetor is accomplished by the use of an unvarying weight controlling the action of the air-valve, instead of depending upon the action of a varying spring, and a definitely designed metering-cone, which can be constructed with exact predetermined characteristics impossible in springs.

In order that those skilled in this art may have a full and complete understanding of the invention and its structural and functional advantages, I have illustrated a preferred embodiment of the invention in the accompanying drawings, forming a part of this specification, and throughout the several views of which like reference characters refer to the same parts.

In these drawings,—

Fig. 1 is a substantially-central, vertical, longitudinal section through the improved carburetor, with certain portions broken away to more clearly illustrate the construction;

Fig. 2 represents the bearing for the sliding hollow stem or mixing tube of the valve, such bearing being shown in section;

Fig. 3 is a vertical cross section on line 3—3 of Fig. 1;

Fig. 4 is a horizontal section on the irregular line 4—4 of Fig. 1;

Figs. 5 and 6 illustrate the ball-valve construction with the ball in different cross-sections; and

Fig. 7 is an enlarged plan view of the valve seat member with which the ball co-operates.

Referring to these drawings, it will be seen that the improved and novel carburetor includes the usual float chamber 10, housing the liquid fuel supply and accommodating the customary float 11 operating a sliding valve 12 through the lever connections 13, 13 to control the inlet passage 14 whereby to maintain a substantially-constant liquid-fuel level 15 in the chamber, the passage or connection

14 being fitted with the common screen 16 and with a pipe connection 17 to the main source of fuel supply.

This float chamber 10 has the familiar removable cover 18 normally demountably held in position by a leaf spring 19 which may be rocked by its handle 21, when desired, into inoperative position, thus permitting the removal of the cover. All of this is of the well known and familiar construction.

The carburetor includes also a chamber or compartment 22 (Fig. 1), the lower internal portion of which is equipped with screw threads coacting with the threads of a plug member 23 (Figs. 1 and 2) having an angular head 24 by which it may be turned and a circular flange 25 adapted to bear on the shoulder or face 26, all as is clearly depicted in Fig. 1.

This chamber 22, the lower portion of which constitutes a starting or fuel well, has two fuel discharge openings communicating with it, the lower one being characterized 85 27 and the upper one being denominated 28.

The passages 29 and 31 (Fig. 3), respectively, of such outlets, which connect with the fuel-supply or float chamber 10, have their own individual needle-valves 32 and 33 whereby the fuel delivered through such nozzles or passages may be separately and 95 easily adjusted or controlled.

In the present structure, the opening 27 is approximately one quarter of an inch below the fuel level in the compartment 10, whereas the opening 28 is about one-half inch above 100 such designated level.

As shown, the notched or fluted heads 34 of the two needle-valves specified are in cooperative relation with a pair of spring-pressed locking or holding pins 35, 35, designed to prevent unintentional turning of the valves, yet permitting their ready manual manipulation for securing the desired or required adjustments.

The bearing member 23 has openings 36 through its sides to its hollow interior, and its upright, central, cylindrical bearing 37 slidably accommodates the hollow stem or shank 38 of a round valve 39 on its top end designed and adapted to coat with an annular valve-port 41 in a horizontal division or partition wall 42 of the carburetor and a trifle larger than the valve, all as is fully shown in Fig. 1. When in its lowermost position substantially closing the port 41, valve 39 is supported by a shoulder 50 on its stem resting on the top of the element 23, as is depicted in Fig. 1.

Below the bearing member 23, the carburetor has a cylindrical, dash-pot chamber 43 closed at its lower end by a threaded plug or closure 44 and containing a reciprocatory plunger or piston 45 fixedly secured on the lower, solid end of the valve-shank 38.

Such plunger or piston has a small bleeder 130

or relief port 46 extended vertically therethrough, and in addition it is supplied with a plurality of larger ports 47 extended through it, the upper ends of the latter ports being normally closed and covered by a centrally apertured disk 48 having limited play or movement on the valve-stem between the piston and a shoulder 49 on the stem.

There is sufficient leakage so that the dash-pot chamber 43 is at all times filled with the liquid fuel, whereby the upward or ascending movements of the valve 39 are retarded or restrained by the dash-pot mechanism, whereas its descent is comparatively free and unrestrained as determined by the opening and closing action of the disk-valve 48 with relation to the ports 47.

The top round wall of the compartment 22, which in cross sections is of the shape indicated in Fig. 1, is supplied with a central, round, air-admission aperture 51 through which the valve stem or shank extends, such hole or port 51 affording means for a downward passage therethrough of more or less of the air which flows through the carburetor.

In order that such port or opening 51 may be controlled or opened more or less as circumstances require, the hollow valve shank or stem 38 is fitted or supplied with a metering-cone 52, which closes the port in more or less degree as the valve 39 rises under the suction to which it is submitted, thus increasing the suction in the chamber 22 at the two different-level fuel openings.

The upright cylindrical passage, or mixing conduit, 53, in the valve-stem 38 (closed at its lower end) has side openings 54 therethrough connecting such internal bore or passage with an inner annular chamber 55 inside of the middle portion of the element 23, and with which the openings 36 connect, so that the chamber 22 is in direct communication with the vertical passage 53 inside of the valve-stem.

Internally, the top of the round valve-member 39 has a series of radial grooves 56 and 57 (Fig. 7), the alternate grooves 56 being somewhat deeper than the remaining or companion alternate grooves 57.

At the center of its top, this valve member has a semi-spherical cavity or recess 58 accommodating a ball-valve 59, and when this ball is resting on its seat in such cavity the lower parts or ends of the tapered grooves 56 are open, at which time the other grooves 57 are closed by the ball.

When the suction is sufficient to raise the ball, then, at least temporarily, all of the radial grooves or passages are open.

A round, centrally-recessed cover-plate 61 is fastened over and to the member 39 by screws 62, 62, leaving an annular space 63 between the two parts 39 and 61, connecting the outer or upper ends of all of the grooves 56 and 57, whereby the contents of the latter

may be delivered or discharged out laterally through this horizontal, shallow, annular gap.

The inner or under surface of the top valve-member 61 is centrally recessed at 60 to receive a portion of the ball-valve, such cavity being of a sufficient size to permit the rise of the ball-valve as described above.

The cylindrical, upright passage 53 in the stem of the valve which connects with the series of radial grooves 56 and 57 in the top of the valve-member constitutes a mixing tube, the suction through which is capable of adjustment or variation by the movements of the ball-valve controlling the grooves 57.

The part 64 of the carburetor represents the means for fastening it to the intake-manifold of the motor, and internally this portion of the structure is equipped with the usual throttle-valve 65, beneath which is the chamber 66 above the valve 39 and forming a portion of the general passage through the carburetor.

The part 67 of the device is for the admission of the outside air to that part of the carburetor above the chamber 22 and beneath the valve 39, and this part of the appliance is fitted with a choke-valve 68, which, however, need not be manipulated for starting the engine, but is sometimes required or desired for its choking effect until after the motor becomes somewhat heated up.

It will be observed from an understanding of this construction that I have removed both fuel orifices or nozzles out of the mixing tube 53, and whereas a high and nearly constant suction is maintained in the latter, a variable suction at the fuel jets is brought about corresponding to the required feed of fuel under varying conditions.

The operation of this carburetor takes place practically as follows:

When the engine is idling, the constant-weight valve 39 almost closes the valve port 41 and the ball-valve 59 is down, closing the grooves 57, but not closing the deeper grooves 56. Most of the air entering the carburetor through the connection 67 flows down through the annular port 51 and past the two fuel openings 28 and 27, but inasmuch as the suction at this time is insufficient to cause a delivery of fuel through the upper opening 28, the air receives all of its charge of fuel through the lower fuel nozzle or opening 27, and the mixture flows through the ports or openings and passages 36, 55, 54, mixing tube 53, grooves 56 and gap 63 into the part 66 of the carburetor above the valve 39, from whence it passes by the throttle-valve 65 into the motor.

As the engine speeds up, the valve 39 rises by reason of the increased suction, which overcomes the weight of the valve, permitting an amount of supplemental air to pass directly through the valve-port 41, and such up-

ward travel of the valve-stem 38 carrying the metering-cone 52 causes a partial closing of the air port 51, bringing about a suction at the fuel nozzles or openings 27 and 28 varying substantially as the square of the engine speed or as the square of the air velocity through the carburetor, although the suction in the mixing tube 53 undergoes only slight, if any, change.

10 Thus the fuel is supplied to the air in such proportion as is required to carburet the shunted air and to maintain the required ratio between fuel and air in the explosive, gaseous mixture.

15 The movements of the constant-weight valve 39 are retarded and the valve prevented from fluttering by the action of the dash-pot construction associated with the lower end of its stem.

20 The metering-cone can be designed to secure the best results desired, and it is to be observed that no springs with their unreliable variable expansion or extension or compression characteristics are employed in connection with this valve,

25 with this valve, its weight alone determining when it will be lifted off of its seat and the extent of such movement which is transmitted directly to the metering-cone.

Such constant-weight valve does not start to 20 open until the suction above the valve has reached an equivalent of approximately fourteen inches water column, the suction on the inside of the mixing tube 53 varying comparatively little regardless of the speed of the 35 engine because of the action of such weight-controlled valve.

The relatively small mixing tube 53 assures the high velocity of flow of gases when the engine is idling, but the construction of the 40 appliance is such that there is an avoidance of excess rarefaction of air or suction at high speeds of the car.

The high velocity in the mixing tube 53 is required to secure the proper intermixture of 45 air and fuel, particularly when the engine is idling, and in general the higher the velocity the better the mixing of the elements of the gaseous mixture.

The metering-cone represents the final adjusting means to secure the correct fuel curve 50 that is to say, to produce the correct fuel ratio to air, which ought to remain substantially constant except that a richer mixture is needed when the engine is traveling slowly or 55 idling and when accelerating.

The combined action of the constant-weight air valve 39, the weight of which corresponds to about fourteen inches water-column suction, and the metering-cone 52, which varies 60 the opening of port 51, produces the same result as an ideal spring with variable tension for the different degrees of compression of the spring, and the value of this improved construction resides in the fact that whereas 65 mechanically the spring can not be controlled

exactly in its action, the shape of the cone can be made approximately that which is desired, and consequently the action of the metering-cone can be predetermined and exactly secured.

70 It will be seen that as soon as the engine or motor is stopped, the so-called starting-well in the lower portion of chamber 22 will be filled with fuel by reason of the connection 27 with the float chamber, and consequently as 75 soon as the engine is started, a rich mixture will temporarily be delivered to the engine, facilitating its starting action. Under quick acceleration, of course, the upward movement of the valve 39 is retarded by the dash-pot mechanism, but the ball-valve 29 is free to rise under such conditions, temporarily or momentarily modifying the suction at the fuel jets, whereby a rich mixture is delivered 80 to the engine to produce the required acceleration until the main valve 39 itself can respond.

85 It is to be understood that the invention is not limited and restricted to the precise and exact details herein presented, and is susceptible of a variety of embodiments, this 90 particular carburetor being subject to change in its various structural elements within comparatively wide latitudes without departure from the substance and essence of the invention and without the sacrifice of any of its 95 material benefits and advantages.

I claim:

1. In a carburetor having first and second air-inlet ports, the combination of a vertically-slidable valve co-operating with said first air-inlet port and adapted to be raised to open said port by the suction present in the carburetor, said valve having an upright tubular stem movable therewith, the passage through which terminates in a discharge orifice in a first chamber above said first air-inlet port, means to retard the opening action of said valve, said second air-inlet port communicating with a second chamber having means for the delivery of fuel thereto and 100 connected to said passage through said tubular stem, a cone on said stem coacting with said second air-inlet port, a throttle-valve 105 for the carburetor above said first chamber, and a valve controlling the passage through 110 said stem freely movable under the action of the suction in said first chamber.

2. In a carburetor having first and second air-inlet ports, the combination of a vertically-slidable valve co-operating with said first 115 air-inlet port and adapted to be raised to open said port by the suction present in the carburetor, said valve having an upright tubular stem movable therewith, the passage through which terminates in a discharge orifice in a first chamber above said first air-inlet port, means to retard the opening action of said 120 valve, said second air-inlet port communicating with a second chamber having means for the delivery of fuel thereto and connected to 125

said passage through said tubular stem, a throttle-valve for the carburetor above said first chamber, and a valve controlling the passage through said stem freely movable under the action of the suction in said first chamber.

3. In a carburetor having first and second air-inlet ports, the combination of a constant-weight vertically-slidable valve co-operating with said first air-inlet port and adapted to be raised to open said port by the suction present in the carburetor, said valve having an upright tubular stem movable therewith, the passage through which terminates in a discharge orifice at the top of the valve, means to retard the opening action of said valve, said second air-inlet port communicating with a chamber having means for the delivery of fuel thereto and connected to the passage through said tubular stem, a throttle-valve for the carburetor above said valve, and a valve controlling the opening of said orifice freely movable under the action of the suction in the carburetor.
- 25 4. In a carburetor having first and second air-inlet ports, the combination of a vertically-slidable valve cooperating with said first air-inlet port and adapted to be raised to open said port by the suction present in the carburetor, said valve having an upright tubular stem movable therewith, the passage through which terminates in a discharge orifice in a first chamber above said first air-inlet port, means to retard the opening action of said valve, said second air-inlet port communicating with the top of said second chamber having means for the delivery of fuel into the lower portion thereof and connected to said passage through said tubular stem, a cone valve on said stem coacting with said second air-inlet port, a throttle-valve for the carburetor above said first chamber, and a valve controlling the passage through said stem freely movable under the action of the suction in said first chamber.

In witness whereof I have hereunto set my hand.

TORBJORN LINGA.
